UNITED STATES PATENT OFFICE.

WILLIAM A. BOLE, OF PITTSBURG, PENNSYLVANIA, ASSIGNOR TO THE WESTINGHOUSE MACHINE COMPANY, A CORPORATION OF PENNSYLVANIA.

TURBINE-ROTOR.

No. 900,700.

Specification of Letters Patent. Patented Oct. 13, 1908.

Application filed March 18, 1905. Serial No. 250,822.

To all whom it may concern:

Be it known that I, WILLIAM A. BOLE, a citizen of the United States, and a resident of Pittsburgh, in the county of Allegheny and State of Pennsylvania, have invented a new and useful Improvement in Turbine-Rotors, of which the following is a specification.

This invention relates to elastic fluid turbines and more particularly to the rotors thereof.

Considerable difficulty has been encountered in turbines of the class described in obtaining a rotor or blade-carrying drum of suitable weight which shall resist distortion due to the combination of lateral fluid pressure and centrifugal force.

The stresses due to centrifugal force are radial, and in a rotor such, for instance, as a flat disk designed to resist these stresses, a lateral fluid pressure will induce strains that will cause the disk to dish. If the flat disk be laterally reinforced to resist this dishing tendency, the resulting rotor will be objectionable in that, by the lugs or reinforcing webs, the resistance to rotation is increased, and the webs will induce disturbing currents within the turbine casing.

Rotors for turbines of the class described must be accurately balanced, because with the high rotational speed encountered, an eccentricity of the center of gravity will cause vibrations in the mounting shaft. To insure a symmetrical and perfectly balanced rotor, and also to reduce what is known as fluid friction between the motive fluid of the turbine and the rotor, it is customary to machine or finish the rotor on all its surfaces. In constructing a rotor that will admit of such machining, forms have been adopted that will readily resist the distorting tendency of lateral fluid pressure, but when subjected to the strains due to centrifugal force, a tendency is induced in them to straighten or flatten out. This distortion, as in the case of the flat disk, results in a decided lateral motion of the rim or periphery of the rotor, which because of the necessarily small working clearances in the turbine, is objectionable.

An object of this invention is, therefore, to produce a rotor that will withstand the tendency to distort when subjected to the combined strains due to centrifugal force and lateral fluid pressure.

A further object of this invention has been

the production of rotors for such turbines, applicable for use in forming either the blade-supporting member or the balance-piston.

In the drawing accompanying this application and forming a part thereof, the single view is a longitudinal section of such a rotor. This rotor, which may be utilized as a balance-piston or blade-support, is formed of two distinct symmetrical and oppositely positioned disks bolted or otherwise suitably secured together.

Referring to the figure: The hubs 1 and 6 are keyed to or otherwise rigidly mounted on the shaft. The converging webs 2 and 5 meet and are connected by screws or bolts 7 at a point adjacent to their respective rims 3 and 4. The hub portions 1 and 6, because of their rigid connection to the shaft, may be considered as one piece and with the integral webs 2 and 5 form a triangular section capable of resisting the combined distorting effect of lateral fluid pressure and centrifugal force.

Lateral fluid pressure on the web 2 will induce in that web a tendency to turn about some point of its connection with the hub 1, but this tendency will be resisted by the web 5, which by the slightest tendency toward yielding of the web 2, is thrown into compression and resisting the distorting tendency, transmits a portion of the fluid pressure to the rotary shaft through the hub 6; that is, the action of one web reinforcing the action of the other, presents a rigid resistance to the distorting tendency of the lateral fluid pressure.

As there will be a tendency in each of the disks to separate and flatten out, when they are subjected to the strains due to centrifugal force, the action of one disk in opposition to that of the other, through the bolts or screws 7, will overcome this distorting tendency, and the rims 3 and 4 will therefore be held rigidly in place. In this construction the distorting tendency of fluid pressure in either direction is rigidly resisted and the tendency to warp or to laterally distort when subjected to the combined actions of lateral fluid pressure and centrifugal force, is overcome, and a light yet rigid construction is produced.

It will be understood that the exact contour or form herewith illustrated and described may be departed from in various particulars and still be embraced by this invention, and that

What I claim as new and useful and desire to secure by Letters Patent is:—

1. In an elastic fluid turbine, a drum consisting of two **Z**-shaped sections combined to resist lateral distortion when subjected to the actions of centrifugal force and lateral fluid pressure.
2. In an elastic fluid turbine, a drum or cylinder consisting of two transversely connected **Z**-shaped cast sections.
3. In an elastic fluid turbine, a drum comprising symmetrically - formed and transversely-connected **Z**-shaped sections.
4. In an elastic fluid turbine, a drum comprising two symmetrically-formed and transversely-connected **Z**-shaped sections.
5. In an elastic fluid turbine, a drum consisting of symmetrically-formed **Z**-shaped sections combined to resist lateral distortion when subjected to the action of centrifugal force and lateral fluid pressure.
6. In an elastic fluid turbine, a drum or cylinder consisting of two transversely connected **Z** shaped integral sections.
7. In an elastic fluid turbine, a drum or cylinder consisting of two **Z** shaped cast sections and means for combining said sections to resist distortion when subjected to the actions of centrifugal force and fluid pressure.
8. In an elastic fluid turbine, a drum or cylinder consisting of two transversely connected **Z** shaped integral sections, and means for combining said sections to resist distortion when subjected to the actions of centrifugal force and fluid pressure.
9. In an elastic fluid turbine, a drum or cylinder consisting of two **Z** shaped integral sections, and means for combining said sections to resist distortion when subjected to the actions of centrifugal force and fluid pressure.
10. In an elastic fluid turbine, a drum or cylinder consisting of transversely connected **Z** shaped integral sections.
11. In an elastic fluid turbine, a drum or cylinder consisting of transversely connected **Z** shaped integral sections, and means for combining said sections.
12. In an elastic fluid turbine, a drum or cylinder consisting of two **Z** shaped sections, and means for combining said sections to resist distortion.
13. In an elastic fluid turbine, a drum or cylinder consisting of **Z** shaped sections, and means for combining said sections to resist distortion.

In testimony whereof, I have hereunto subscribed my name this 14th day of March, 1905.

WILLIAM A. BOLE.
